Primary Examiner — Eric L Goodman*Assistant Examiner* — Amy C Wierenga(74) Attorney, Agent, or Firm — Banner & Witcoff, Ltd.(57) CLAIM

The ornamental design for a garment, as shown and described.

DESCRIPTION

FIG. 1 is a front perspective view of a garment showing our new design;

FIG. 2 is a second front perspective view thereof;

FIG. 3 is a front view thereof;

FIG. 4 is a right side view thereof;

FIG. 5 is a left side view thereof;

FIG. 6 is a front perspective view of an alternative embodiment of a garment showing my new design;

FIG. 7 is a second front perspective view thereof;

FIG. 8 is a front view thereof;

FIG. 9 is a right side view thereof; and,

FIG. 10 is a left side view thereof.

The broken lines immediately adjacent to the shaded area define the bounds of the claim and form no part thereof. The broken lines showing the remainder of the garment represent portion of the garment that form no part of the claim.

1 Claim, 10 Drawing Sheets(56)
